UNITED STATES PATENT OFFICE.

CHESTER W. LARNER, OF CLEVELAND, OHIO.

HYDRAULIC VALVE.

1,195,237.

Specification of Letters Patent. Patented Aug. 22, 1916.

Application filed March 5, 1914. Serial No. 822,565.

To all whom it may concern:

Be it known that I, CHESTER W. LARNER, a citizen of the United States, residing at Cleveland, in the county of Cuyahoga and 5 State of Ohio, have invented certain new and useful Improvements in Hydraulic Valves, of which the following is a specification.

Hydraulic or gate valves employed for 10 example to control the supply of water from a forebay or pond to a power-house for use in operating turbines are usually of ponderous form, are submerged, and require elaborate mechanism for operating 15 them.

The object of this invention is to simplify the construction and mode of operation of such valves, and generally stated the invention contemplates a valve operating on the 20 principle of flotation. With this and other objects in view, the nature, characteristic features and scope of the invention will more readily be understood from the following description taken in connection with 25 the accompanying drawing, forming a part hereof, wherein—

Figure 1 illustrates in central vertical section and elevation a gate-house installation embodying features of my invention. 30 Fig. 2 is a similar view of a modification.

Referring to Fig. 1, the numeral 5 designates a penstock or conduit which opens vertically into a forebay or pond 6. The gate-house 7 is of generally circular form, 35 the water being admitted around the circumference and flowing to the valve between the piers 8, the number of which may vary.

The valve consists of a hollow plug or 40 cone-shape shell or body 9 equipped with a central bore or passage which is prolonged by a hollow stem 10 ranging upwardly. A guide or roller path 26 which co-operates with the stem acts to center the valve and 45 to prevent it from tipping. As a further means to prevent tipping of the valve, lugs 50 11 are provided carrying rollers 12 which run on the piers 8 and thus serve to guide the valve and maintain it in a true vertical 55 position in the valve-way formed by said piers. The hollow stem 10 is useful for the accommodation of operating mechanism and as a means of access to the interior of the valve when it is submerged. The supply and discharge of water to and from

the valve shell are controlled by a drain-valve 13 suitably seated below the passages 14, and whereof the spindle 15 is operatively connected with a suitable actuating device, for example the motor 16.

When the valve is closed, that is to say when the drain-valve 13 is seated, it is full of water and resting of its own weight on seat 17, embedded in the foundation of the gate-house. In order to raise the valve, 65 water must be discharged from the interior thereof until the displacement is sufficient to float the weight of the valve. To effect this it is important that the conduit or penstock 5 shall be full of water under the 70 same head as in the forebay. This may be accomplished by means of a by-pass 18 having an independent gate (not shown). Obviously in order to flood the conduit via the by-pass it is of course necessary that the 75 conduit be provided with a stop-valve such as the conventionally illustrated valve 19 to prevent the water from flowing out of the conduit as fast as it enters. This, however, is the ordinary condition met with in the 80 construction of a water plant such as this valve is particularly adapted to. The conduit 5 conveys the water to the power-house whence it is distributed to the turbines and each turbine is equipped with its own valve. 85

The floating of the valve may be accomplished in three ways, viz:

(a) If the penstock or conduit is drained sufficiently enough water may be discharged by opening the drain-valve 13. The latter and the passages 14 leading to it through the hollow stem are located at such an elevation as to drain only enough water to float the valve the proper distance. When a sufficient quantity of water has been displaced, the drain-valve is closed and the penstock is flooded in the manner aforementioned. The rising water in the penstock causes the valve to float off its seat to a certain predetermined level depending 100 upon the amount of displacement provided. When the valve is floated to the proper position, the lugs 11 carrying the guide rollers are above the automatic latches 20 the function of which is to prevent the valve 105 from sinking in the event of leakage.

(b) A sufficient quantity of water may be discharged from the valve when in its closed position by means of air pressure from a compressor 21 located in the gate-house.

With this method it is necessary of course to seal the top end of the hollow stem, as at 25. Air pressure introduced through pipe 22 will then displace water through pipe 23. If the penstock is flooded in the manner previously described, the valve will float as soon as the necessary quantity of water has been discharged from the valve. The bend 24 in channel 23 is located above the water level in the forebay so as to prevent backflow without the aid of a check-valve.

(c) The valve may be floated by using the ordinary and well known pump or ejector for effecting the displacement of water contained therein.

The operation of closing or seating the valve is the same no matter what method is used to raise it. It consists simply of opening the drain-valve 13 when the valve is floating, admitting water to the interior of the valve and displacing air through the hollow stem. The valve thereupon sinks of its own weight and rests on its seat. A valve such as described is particularly useful when the water in the forebay is shallow for the conical base serves to direct the flow into the conduit.

In the modification, Fig. 2, I have shown a valve system for use with a greater depth of water than is represented in the first example. The valve-body consists of a shell 27 that is open at the bottom and which co-operates with a valve-seat 28. Extending upwardly from the valve and communicating directly with the open bottom thereof is a hollow stem 29 closed at the top and which co-operates with a roller path 30 whereby the valve is centered and prevented from tipping. As in Fig. 1, the valve-body may be equipped with rollers 31 which track the piers 8. At 32 is represented a suitable air pump or compressor, and 32' represents a hose or other suitable flexible connection intermediate the pump and the valve-stem for conveying air to the latter. It is evident that the valve may be floated by supplying air thereto in the manner indicated. The valve body 27 is a substantially bell shape structure, that is to say it has a flaring open bottom, and constitutes with its complementary communicating hollow stem a chambered part or float adapted for the free ingress and egress of water. Obviously no drain valve is necessary because of this structure and arrangement. It follows that when air is pumped into the stem it acts upon the column of water therein and unseats the valve. Upon releasing the air pressure the water is free to rise in the stem and reduce the buoyancy of the valve which will thereupon gravitate to its seat. The air pressure is relieved in any suitable way, but the practice is to use a single flexible connection 32' for both supplying and discharging.

Having described the nature and objects of the invention, I claim:

1. A valve and its seat, said valve consisting of a buoyant shell adapted to the seat and having an upwardly directed communicating hollow stem closed at its top, and means operatively connected with the stem for supplying it with fluid pressure. 70

2. A valve and its seat, said valve consisting of a buoyant shell adapted to the seat 75 and having an upwardly directed communicating hollow stem closed at its top, means operatively connected with the stem for supplying it with fluid pressure, and a valve-way including means for engaging the shell 80 to hold it away from its seat in the event of leakage of pressure.

3. The combination of a forebay, a penstock having a valve-seat, a valve adapted to be seated in response to the application 85 of internal weight or pressure and to be unseated upon the removal of said weight, said valve consisting of a shell adapted to the seat and having a communicating upwardly directed hollow stem which is sealed at the 90 top, and means operatively connected with the stem for supplying or relieving pressure.

4. The combination of a forebay, a penstock having a valve seat, a valve adapted to be seated in response to the application 95 of internal weight or pressure and to be unseated upon the removal of said weight, said valve consisting of a shell adapted to the seat and having a communicating upwardly directed hollow stem which is sealed at its 100 top, a gate house having means co-operating with the stem for centering the valve, and fluid connections operatively disposed with respect to said stem.

5. The combination of a forebay, a penstock opening vertically therein and having a valve-seat, a gate house having a valve-way, and a valve adapted to said seat and having a vertical range of movement in said valve-way and having a chambered part 110 open on the penstock side, a hollow stem extending upwardly from the valve and communicating with the chambered part thereof, and a flexible connection for supplying pressure to the stem. 115

6. The combination of a forebay, a penstock opening vertically therein and having a valve-seat, a gate house equipped with a valve-way, a valve adapted to said seat and valve-way and consisting of a chambered 120 float open on the penstock side and equipped with a vertically extending hollow stem, a guide for the same, and means for supplying pressure to the float through the stem.

7. The combination of a forebay, a penstock opening vertically therein and having a valve-seat, a gate house equipped with a valve-way, a valve adapted to said seat and valve-way and consisting of a chambered 125 float open on the penstock side and equipped 130

with an upwardly directed communicating hollow stem, a guide for the same, and a guide for the float including latches for holding the float in raised position.

5 8. The combination of a forebay, a pen-
stock having a valve seat, a valve adapted
to be seated in response to the application
internally thereof of weight or pressure and
to be unseated upon the removal of said
10 weight, said valve consisting of a shell
adapted to the seat and open on the pen-
stock side and having an upwardly directed
hollow stem, and a gate house having sepa-
rate ways with roller paths for the valve
15 and its stem.

9. The combination of a forebay, a pen-
stock having a valve-seat, a valve adapted
to be seated in response to the application
internally thereof of weight or pressure and
20 to be unseated upon the removal of said
weight, said valve consisting of a basal float

part adapted to said seat and having a cen-
tral upwardly extending hollow stem, fluid
pressure connections operatively disposed
with respect to the stem, and an independ-
ent drain valve for the valve. 25

10. The combination of a forebay, a pen-
stock having a valve-seat, a gate house hav-
ing a valve-way, a valve in said valve way
movable vertically with relation to said seat 30
and consisting of a centering hollow stem
closed at its top and terminating in a float
adapted to said seat, an air compressor, and
and a flexible connection intermediate the
same and said stem. 35

In testimony whereof I affix my signature
in presence of two witnesses.
